UNITED STATES PATENT OFFICE.

KINNEY C. HOXIE, OF DULUTH, MINNESOTA.

LADLE-HOOK.

1,086,772.

Specification of Letters Patent. Patented Feb. 10, 1914.

Application filed November 18, 1912. Serial No. 732,035.

To all whom it may concern:

Be it known that I, KINNEY C. HOXIE, a citizen of the United States, and resident of Duluth, in the county of St. Louis and State of Minnesota, have invented certain new and useful Improvements in Ladle-Hooks, of which the following is a specification.

My invention comprises an improved form of device for connecting a crane to a ladle, and is particularly adapted for use in mills where very large and heavy ladles are used for conveying molten metal.

In ordinary practice a ladle is provided with trunnions on opposite sides and when it is desired to transport the ladle, open hooks of the goose-neck type carried by a crane are swung under the trunnions so that the ladle may be raised. It is evident that in an open hook of this type, the strain is all to one side of the center line of the pull, and that such a hook is subjected to very severe transverse stresses, resulting in breakage with consequent disastrous results due to the release of a large quantity of molten metal.

The purpose of my invention is to provide a ladle hook or bail of such construction that these transverse stresses are avoided and the vertical pull or stress is taken by two practically vertical members.

In handling a large ladle full of molten metal it is desirable that the design of the ladle hooks or bails shall be such that the craneman overhead may be able to secure the engagement of the ladle hooks, or bails, with the trunnions on the ladle without any person having to place hooks in position, or approach the ladleful of hot metal. Consequently, the engaging and disengaging of the hooks or bails from the trunnions must be accomplished by two motions—first, a motion toward the ladle to get the hooks beneath the trunnions, and second, a vertical motion to engage the hooks with the trunnions. When it is desired to release the ladle the operations described are reversed. I have therefore devised a ladle hook carried by the crane and operated by a craneman at a distance, the parts being arranged whereby the stress on the hook is almost entirely tensile, the bending tendency of the goose-neck hook being overcome.

My invention will be more readily understood by reference to the accompanying drawings, wherein,

Figure 1 is a side elevation of a ladle and a pair of depending crane hooks or engag-

ing elements ready for engagement with the ladle trunnions; Fig. 2 is an enlarged front elevation of one of the hooks; Fig. 3 is a section on the line 3—3 of Fig. 2; Fig. 4 is a bottom plan view of one of the hooks; Fig. 5 is a fragmentary enlarged section on the line 5—5 of Fig. 3, showing a ladle trunnion in place, and Fig. 6 is a side elevation of a modification of the construction heretofore described.

Referring more particularly to the drawings it will be seen that a ladle 10, having trunnions 11, is rested upon a support or truck 12. The trunnions are provided with peripheral flanges 13, co-operating with a part on the ladle hook in order to prevent the endwise removal of said hook, as will be later described. The ladle hooks 14, of which there are two, are pivoted at 15 to a spacing frame work 16, carrying pulleys 17, on which the crane cables 18 are mounted. The ladle hooks 14 are provided at their lower ends with enlarged elongated loops or eyes 19. Both the looped portion and the shank are constructed at an angle to the longitudinal axis of their pivots 15 and are mounted oppositely: that is, with the angles oppositely disposed, both of the loops facing outwardly. These loops are spaced in order that the outer strap of each loop will clear the widest point of the trunnions of the ladle, whereas the inner straps are considerably within the plane of the trunnions.

Within the base of the loop I mount a casting 20, having depending legs which straddle the loop. These legs are apertured to accommodate the bolts 21, by means of which a bar 22 is united to the two legs and secures the casting rigidly to the loop. The casting is provided with guides 23 on its bottom and side walls at the point where it lies between the straps of the loop. The portion lying within the loop is of different heights, one portion 24 extending up substantially a half of the extent of the loop whereas the lower extension 25 is shorter and is terminated on a horizontal line passing through the center from which the arc forming the lower edge of the loop is struck. The reason for this will be obvious when it is desired to insert or remove the casting.

In order to accomplish such insertion or removal, the casting is disconnected from the bar 22 and raised until the depending legs 20 are within the plane of the loop. The casting is then rotated to the right as viewed

in Fig. 2, until the flanges 23, on both sides of the casting are free from the side members of the loop, whereupon the casting may be worked out of the opening with ease. A bearing or cradle portion 26 is formed integral with the casting 20, and is angularly positioned with respect to the loop and the remainder of the casting; that is, the axis of the bearing is coincident with the axis of the trunnions 11 and at right angles to the pivot pin 15. As a part of the bearing I provide the extension having a groove 27 therein, which receives the flange 13 of the trunnion and prevents longitudinal movement of the parts when associated. This extension or groove 27 has only a quarter of a circle, one side therefore of the bearing 26 being open.

It will be seen by reference to Fig. 1 that the hooks are lowered by the crane to a point where the upper or unobstructed portion of the loops 19 is opposite the trunnions 11; the hooks are then moved sidewise until the trunnions enter the enlarged portions of the openings whereupon the hooks are lifted, the trunnions seating in the bearing 26, and the flange 13 in the groove 27. The cradle is thus securely held and may be moved as desired. The disconnecting action is the reverse of that described for connecting, all of the actions being performed without the assistance of the workmen near the ladle.

In Fig. 6 I have shown a modification in which a U-shaped casting is employed, both the hooks being integral with a bail which may be attached to the crane cables. In this construction the bail has an upper portion 28, and depending legs or loops 29, having an offset 30 therein. The operation is identical with that of the construction heretofore described. The former construction is preferable in that a renewable casting forming a bearing is provided. As this part becomes worn it may be removed and renewed without discarding the hooks. In the construction of Fig. 6 the trunnions 31 of the ladle are provided with outer peripheral flanges 32 to prevent the possible separation of the legs of the bail.

In the appended claims a seat is understood to include a bearing portion for the trunnions of a ladle, it being immaterial whether such seat portion is integral with

the depending members or separate therefrom.

It will be obvious that other modifications may be made and such as are within the scope of my claims I consider within the spirit of my invention.

I claim:

1. In a device of the class described, the combination of a spacing member, legs depending downwardly therefrom, said legs being provided with slots at their lower end, the material at one side of each slot being laterally displaced, seats or bearings being provided at the bottoms of the slots, the horizontal distance between the bearing portions of the slots being less than the distance between the displaced portions of the material surrounding the slots, substantially as described.

2. In a device of the class described, the combination of a spacing member, legs depending from said member, and having loops in their lower ends said loops providing seats for the trunnions of a ladle, portions of the material composing the loops being angularly displaced, said displaced portions being located a horizontal distance apart greater than the distance separating the bearing portions of said loops, substantially as described.

3. In a device of the class described, the combination of an upper spacing member, legs depending from said member and having looped lower ends, said loops providing aligned seats for the trunnions of a ladle, one side member of each loop being displaced laterally beyond its bearing portion whereby to permit the entrance of ladle trunnions to the loop, substantially as described.

4. In a device of the class described, the combination of a spacing member, legs depending therefrom, said legs having slots at their lower ends providing aligned bearings, the material at one side of each slot being displaced laterally, the horizontal distance between said bearings being less than the horizontal distance separating the displaced portions of said legs, substantially as described.

KINNEY C. HOXIE.
